United States Patent Office:

E. B. REQUA, OF JERSEY CITY, NEW JERSEY.

Letters Patent No. 71,789, dated December 3, 1867.

IMPROVEMENT IN LAMP-CHIMNEYS.

The Schedule referred to in these Letters Patent and making part of the same.

TO ALL WHOM IT MAY CONCERN:

Be it known that I, E. B. REQUA, of Jersey City, in the county of Hudson, and State of New Jersey, have invented a new and improved Lamp-Chimney; and I do hereby declare that the following is a full, clear, and exact description thereof, which will enable others skilled in the art to make and use the same; reference being had to the accompanying drawings, forming part of this specification.

This invention consists in a new and improved shape or form of the chimney, whereby the same is kept at an equal distance from the flame all around, and the usual contraction of the chimney above the flame avoided, whereby the chimney is subjected to a uniform degree of heat all around, and the liability to breakage greatly reduced. In the accompanying sheet of drawings—

Figure 1 is a side view of my invention.

Figure 2, a vertical section of the same, taken in the line $x x$, fig. 1.

Figure 3, a horizontal section of the same, taken in the line $y y$, fig. 1.

Similar letters of reference indicate corresponding parts.

The chimney may be blown either in moulds or otherwise, and of flat form, that is to say, much wider in one direction than in the other, as will be seen by referring to figs. 1 and 2. The lower part of the chimney is of flattened bulb-form, as shown at A, in fig. 1, the flat sides being concave or pressed inward, as shown at $a a'$, the outlines of the concaves being distinctly shown in fig. 1. The chimney gradually tapers from its lower bulb portion, A, upward, as shown clearly at B in fig. 1, the usual shoulder formed by a quick or sudden inward curvature of the chimney being avoided. The shape of the chimney directly around the flame is shown clearly in fig. 3, the dotted line indicating the flame. By this shape or configuration of the chimney the latter will be evenly heated all around, and not be liable to break under unequal expansion by heat.

I claim as new, and desire to secure by Letters Patent—

A lamp-chimney of flat form, or wider in one direction than in the other, with the flat sides made concave and the upper part of the chimney, above the lower bulb part, made with a gradual taper, substantially as herein set forth.

The above specification of my invention signed by me, this sixteenth day of October, 1867.

E. B. REQUA.
